(No Model.)

C. W. STIFF.

CAR STARTER.

No. 251,386.

Patented Dec. 27, 1881.

UNITED STATES PATENT OFFICE.

CHARLES W. STIFF, OF FOXBOROUGH, MASSACHUSETTS.

CAR-STARTER.

SPECIFICATION forming part of Letters Patent No. 251,386, dated December 27, 1881.

Application filed October 6, 1881. (No model.)

To all whom it may concern:

Be it known that I, CHARLES WYER STIFF, a citizen of the United States, residing at Foxborough, in the county of Norfolk and State 5 of Massachusetts, have invented certain new and useful Improvements in Car-Starters, of which the following is a specification.

This invention relates to devices attached to street-cars, railway-cars, &c.; and it consists in a system of levers adapted to be connected to and disconnected from the wheels, so that when the horse, engine, or other motive power is first started the wheels will be acted upon to revolve them a short distance 15 and assist in overcoming the inertia of the car, &c., as hereinafter set forth.

In the drawings I illustrate the mechanism by which the above objects are attained, Figure 1 being a sectional side elevation, Fig. 2 20 a plan view, and Fig. 3 a cross-sectional view, of the truck and bottom frame-work of an ordinary street-car with my improvements attached thereto. Fig. 4 is an enlarged perspective view of a portion of the rim of one of the 25 wheels and its operating-levers. Fig. 5 is a front view of the levers for throwing the pulling-levers into gear with the wheels. Fig. 6 is a front view, Fig. 7 is a plan view, and Fig. 8 30 is a cross-sectional view, enlarged, of the lower end of one of the pulling-levers, showing one method of arranging it, while Fig. 9 is an enlarged perspective view of the same with the parts disconnected.

A' A² are the front wheels, A³ A⁴ are the rear wheels, B' B² are the axles, C' is the main frame-work of the bottom of the car, and C² the platform-frame, all arranged in the ordinary manner of a street-car, which I have used for the purpose of illustrating the manner of applying my invention.

D is the draw-bar, to which the horses are attached, and runs back through the cross-timbers of the frame C' and ends in a long cross-bar, E, through which it is bolted. The 45 bar E is arranged to rest through hangers a' a², attached to the lower side of the frame C', and the draw-bar is surrounded, between the cross-bar E and the end timber, C³, of the frame C', by a coiled spring, b, so that by pulling 50 upon the draw-bar D the cross-bar E will be drawn along the hangers a' a² and the

spring compressed against the cross-timber C³, and then when the power is removed the spring will return the cross-bar to its original position. By this means an ordinary spring draw- 55 bar is produced.

c e are small hook-shaped lugs formed upon the inner surfaces of the rims of the rear wheels, A³ A⁴, and opposite to which small levers d' d² are pivoted in the frame C', and connected at 60 their tops by rods G' G² to the ends of the cross-bar E, as shown.

H' H² are two long levers, pivoted at e' e² to the frame C', and with their rear ends curved and bent, as shown at g' g², upward and outward, to bring them opposite to the levers d' d², so that by forcing the forward ends, h' h², 65 toward each other the bent ends g' g² will be forced outward and throw the levers d' d² in contact with the lugs c. The levers d' d² will 70 be supplied with springs to throw them inward, and hold them from contact with the lugs, except when thrown outward by the levers H' H². By this means the pulling of the draw-bar forward will not affect the starting 75 mechanism, which is only operative when the levers H' H² throw the levers d' d² into gear with the lugs c.

Many methods may be used to draw the ends h' h² of the levers H' H² toward each other, but 80 I have shown but one—viz., a double-acting lever, K, and rods i' i², (see Fig. 5;); but any other suitable method may be employed.

The operation of the starter is as follows: 85 When the car is ready to be started the operator throws the lever K over, forcing the levers d' d² outward in contact with the rims of the wheels A³ A⁴ and behind two of the lugs c, (one on each wheel,) and then, when the power is applied to the draw-bar, the levers 90 d' d², acting upon the lugs c, will revolve the wheels and assist greatly in overcoming the inertia. Just as soon as the operator feels the car begin to move he releases the lever K and returns the levers H' H² to their former position; but the levers d' d², having been drawn in behind the hooks on the lugs c, will be held 95 in contact therewith, but will not press outward upon the wheels, by reason of their springs holding them inward. By the time the strokes 100 of the levers d' d² are completed the car will have made such headway that the wheels will

travel faster than the levers d' d^2 . Hence the lugs c will leave them and permit their springs to throw them inward, so that they will not be struck by the next set of lugs.

5 By this arrangement a car-starter will be produced that may be utilized as an ordinary spring draw-bar, and then by a simple turn of a lever, K , the outer rims of the wheels may be connected to the draw-bar and a car-starter 10 formed.

By forming the lugs c in the hooked form it is not necessary to hold the levers d' d^2 in contact with the lugs or wheels, as the lugs themselves hold the levers as long as the necessity 15 for it remains, thus avoiding the constant outward pressure which would be necessary if the lugs had no hooks upon them. In Figs. 6, 7, 8, and 9 is shown one method of arranging the levers d' d^2 , which require both a lateral and a 20 forward and backward motion. A large plate, m' , is pivoted in a V-shaped cavity, n' , in the frame C' , and into the face of this an angular notch or cavity, m^2 , is cut, and adapted to receive the lower rounded end of one of the levers, d' or d^2 . The same bolt, t' , which holds the plate m' also passes through the lower end of the lever d' or d^2 , and is secured therein by a pin, t^2 , passing through it, and a collar, t^3 , on the lever d' or d^2 . The hole through the 25 collar d^3 and the lever d' or d^2 , through which the bolt t' passes, is elongated up and down, so that the lever has the necessary outward and inward play to enable it to be thrown outward and inward by the levers H' H^2 , while 30 at the same time the pin t^2 holds it attached to the bolt t' . Springs m^3 connect the levers 35

d' d^2 with the disks m' , so that they will be held inward from contact with the wheels A^3 A^4 when not thrown out by the levers H' H^2 . By this arrangement a broad bearing-surface 40 for the movement of the levers d' d^2 is produced and much unnecessary friction avoided, while at the same time all the required movements are obtained.

This invention may also be applied to trucks 45 or wagons for hauling heavy loads, and may be attached to either the forward or rear wheels, or both, or arranged to operate from both ends.

What I claim as new is—

1. A car-wheel provided with hook-shaped 50 lugs c , in combination with a lever, d' , and means for throwing said lever behind the lug and also in front of the wheel as soon as the lug passes from the lever, the said lever being drawn forward by the power moving the car, 55 substantially as set forth.

2. The combination and arrangement of the wheels A^3 A^4 , having the hooked lugs c , the levers d' d^2 H' H^2 , and draw-bar D E , and connecting-rods G' G^2 , substantially as set forth. 60

3. The plate m' , frame C' , bolt t' , spring m^3 , and pin t^2 , in combination with the levers d' or d^2 , and wheels A^3 or A^4 , having the lugs c , substantially as set forth.

In testimony whereof I have hereunto set 65 my hand in the presence of two subscribing witnesses.

CHARLES WYER STIFF.
